EAVES TROUGH HANGER

Frank R. Payne, Peru, Ind.

Application May 10, 1937, Serial No. 141,788

2 Claims. (Cl. 248—48.1)

This invention relates to new and useful improvements in hangers of the character especially designed for supporting eaves troughs.

The principal object of the present invention is to provide an eaves trough hanger which will greatly simplify the job of removing and replacing troughs when they become dilapidated.

Another important object of the present invention is to provide an eaves trough hanger including an anchoring member for the suspending means which is a permanent fixture and which is not affected when troughs are being removed and replaced.

Other important objects and advantages of the invention will become apparent to the reader of the following specification.

In the drawings:

Figure 1 represents a fragmentary front elevational view of the hanger installed for use.

Figure 2 is a fragmentary vertical sectional view taken substantially on the line 2—2 of Figure 1.

Figure 3 is a horizontal sectional view taken substantially on line 3—3 of Figure 2.

Figure 4 is an enlarged fragmentary vertical sectional view taken substantially on line 4—4 of Figure 3.

Figure 5 is a top plan view of a modified trough clamp and also shows the suspending member in transverse section.

Figure 6 is a fragmentary top plan view of the anchor in blank form.

Referring to the drawings wherein like numerals designate like parts, it can be seen that numeral 5 represents the conventional form of trough having the rolled edge 6. Numeral 7 generally refers to the clamp while numeral 8 generally refers to the suspending element. The anchoring means is generally referred to by numeral 9.

The anchoring means consists of the elongated plate 10 bent on the longitudinally extending line 14 to provide the vertical flange 13 and the front end of the plate forms a lip 11 which is bent on the transverse line 15 to a perpendicular position as shown in Figure 1. This lip is separated from the front end 12 of the vertical flange 13 by a slit 10 which forms a continuation of the bend line 14 and said end 12 has its front edge sloping as at 17 so that this edge will also be perpendicular, or substantially so, when the plate is attached to a sloping roof as shown in Figure 2 which also shows the front end of the vertical flange 13 projecting from the lower edge of the roof and beyond the bent down lip 11. A saw

cut 19 is made in the lower edge of the sheathing 18 of the roof to receive the flange 13 and the plate 10 is attached to the sheathing by nails or the like passing through the holes formed in the plate as shown in Figures 1 and 2. A slot 16 is formed in the plate slightly inwardly of the fold line 15. The lip 11 should be bent so that it will be perpendicular irrespective of the slope of the roof.

The suspension element 8 is formed from a pair of wires *a* and *b* which have their upper ends passed upwardly in rear of the lip 11 and through the slot 16 and are then bent downwardly in front of the lip and their ends twisted around other portions of the wires directly under the lip, said other portions extending downwardly through the member or clamp 7.

The lower ends of these suspending wires *a*—*b* are twisted together and then disposed through an opening in the plate 20 of the clamp means 7 and brought back upwardly through other openings and then bent flatly against the top surface of the plate 20 as substantially shown in Figure 3.

One end of the plate 20 has an elongated sheet metal strap 21 secured thereto and this strap extends under the trough 5 and up over the rolled edge 6 thereof. A substantially heavy dove-tailed tongue 22 extends from the opposite end of the plate 20 and is bent over the free end of the strap 21, thus holding the clamp 7 firmly to the trough 5.

A modified form of clamp is shown in Figure 5 and generally referred to by reference character 7a. This clamp consists of the elongated plate 20a provided with a wide end portion 20b which has a slot 20c therein for receiving the free end of the elongated strap-like extension 21a which extends from the opposite end of the plate 20a. Obviously, this strap 21a is disposed around the trough 5 and its end inserted through the slot 20c and bent downwardly.

While the foregoing specification sets forth the invention in specific terms, it is to be understood that numerous changes in the shape, size, and materials may be resorted to without departing from the spirit and scope of the invention as claimed hereinafter.

Having described the invention, what is claimed as new is:

1. An eaves trough hanger comprising an anchor including a plate having a depending flange, means for attaching the plate to a roof, the lower end of the plate being bent downwardly to provide a lip and said lip being separated from the

- lower end of the flange which extends outwardly beyond the lip and said plate having a hole therein spaced inwardly from the lip, a suspension element formed of bendable material and having its upper end passing upwardly in rear of the lip through the opening in the plate and then brought downwardly in front of the lip and fastened to another portion of the element under the lip and a trough engaging clamp connected 10 with the lower end of the suspending element.
2. An eaves trough hanger comprising an anchor including a plate adapted to be connected to a roof part and a depending lip at the outer end of the plate located in front of the eaves of 15 the roof and said plate having a hole therein slightly in rear of the lip, a suspending element

including a pair of wires having their upper ends passing in rear of the lip through the hole and then bent downwardly over the front of the lip and having their ends connected with the rest of the wires under the lip, the lower portions of the wires being twisted together and a trough engaging clamp having holes therein, through the center one of which the wires pass with one wire extending toward one end of the clamp and upwardly through a hole therein with the terminal bent over the clamp and the other wire extending under the clamp toward the other end thereof and through another hole with its terminal bent over the top of the clamp.
